UNITED STATES PATENT OFFICE.

EDWIN J. SIBLEY, OF WESTBURY, NEW YORK.

CASEMENT WINDOW.

Application filed February 23, 1927. Serial No. 170,102.

This invention relates to improvements in casement windows and has particular reference to improvements in the hinges for such windows. The invention is particularly applicable to metal casement windows.

One object of the invention is to provide a hinge for a metal casement window which shall function and appear as an ordinary hinge, but which permits the window to be moved into a given position to permit cleaning of both sides of the window from the inside of the room. Another object is to provide a hinge including certain novel features of adjustment. A further object of the invention is to embody the features as aforesaid in a hinge which does not require special arrangements for crating and shipping. Other objects will appear as this specification proceeds.

In the manufacture of metal casement windows there is necessarily a plus and minus factor in the fit of the window sash against the frame. That is to say, when the window is closed, it will be found that the edge of the sash nearest the hinges, rarely, if ever, fits tight against the frame for the entire length of the window. This occurs because of an inherent tendency in the metal to spring or get out of alinement. It is also due to handling and shipping. The industry recognizes this objectionable fault, and it has been proposed to eliminate the same, either by individual fitting of the window on the spot, or by providing means, such as an eccentric bushing within the hinge pivot, for adjusting the hinged edge of the window so as to obtain a tight fit.

Individual adjustment or fitting of each window is impracticable for obvious economic reasons, besides being unreliable. Adjustment by means of a turnable bushing is found only in connection with offset hinges and for that reason is objectionable.

This invention provides a hinge which is mounted close to the window, thus permitting shipping in bundles, obviously an economic factor of importance. Second, this invention provides a hinge permitting the window to be moved into off-set position without using an off-set hinge. Third, means are provided for adjusting the fit of the window, and fourth, securing and releasing means are provided to permit the operation of off-setting the window.

The means provided are such that they fall within the scope of the ordinary manu-

facture of metal casement window, are simple and effective in operation and not expensive.

The invention is illustrated in its preferred form in the accompanying drawings in which

Fig. 1 is a view of a casement window and frame showing the hinge side thereof and with parts broken away.

Fig. 2 is a view looking from the left in Figure 1 with the window open, the frame in section and parts broken away. This view is also in the direction of arrow 2 in Figure 3.

Fig. 3 is a detail perspective view showing the adjusting and locking means.

Fig. 4 is a plan view looking in the direction of arrow 4 in Figure 1.

Fig. 5 is a sectional view on line 5—5 in Figure 2, but shows the window closed.

Fig. 6 is a plan view similar to Fig. 4 but shows the window in open off-set position.

Fig. 7 is a perspective view of a part of the hinge.

All frames and sashes of modern metal casement windows are made of Z-bars. In the drawings the numeral 10 denotes the frame and the outer flange is marked 11. The window sash Z-bar is marked 12 and its outer flange 13. The member or angle piece marked 14 in Figures 4, 5 and 6 represents the usual jamb angle for mounting the window in masonry or concrete.

The window is provided with an upper and a lower hinge. As the construction is alike, only one will be described, though certain parts are reversed in the two hinges. The hinge is a double hinge, that is it permits the window to open and to be swung in open position into an off-set position. Each hinge consists of a relatively fixed hinge plate and a relatively movable hinge plate which are bored so as to be united and pivoted on a hinge pin.

Referring first to Figure 7, the reference numeral 15 denotes the fixed hinge plate having holes 16 for attachment to the vertical frame Z-bar 10 by means of bolts 17, see Figures 4, 5 and 2. The bolts also pass through the jamb angle 14 when such is used. The fixed hinge plate may also be provided with a wing 18 which passes through the flange 11 and lies in over the horizontal frame bar 10 and is screwed fast with a screw 19. At the bottom of Figures 1 and 2 the wing 18 appears attached to the lower horizontal frame 10. The plate 15 is bored as at 20 to receive the hinge pin 21.

The movable hinge plate is in the form of a long hinge leaf 23 having two pivot lugs 24, 24 bored to receive the hinge pin 21 and fitted into the fixed hinge plate 15. The other 5 end of the plate 23 is hinged at 25 to a hinge lug 26 secured to the window. It will therefore be seen, that the window may be swung open on the hinge pin 21 and thereafter the window may be swung away from the plate 10 23, turning on the hinge 25, and be moved into off-set position shown in Figure 6. This type of hinge is known to the art.

In order to adjust the window to fit tight along the hinge edge, means are provided at 15 the corners for forcing them against the window frame. In this instance there is provided both at the top and at the bottom an adjusting screw 27 which is screwed into the outer flange 13 of the window bar 12 and which 20 screw bears against the inside of the movable hinge plate 23 as best seen in Figure 5.

When the window is closed, it is secured by means of a catch at the free edge in the usual manner and therefore not shown. In the 25 closed position, therefore, the hinge edge 28 of the window, may be forced tight against the outer flange 11 of the frame 10 by screwing the adjusting screw 27 outward against the hinge plate 23. Such adjustment made at 30 the installation will be permanent and the window will close tight.

During the normal operation of the window, it is obvious that some means must be provided to secure the window to the hinge 35 plate 23 and whereby the parts 23 and 26 will operate as one piece. Such securing means must also be arranged so that they may be released to permit swinging the window on the hinge 25. As best seen in Figure 6, the hinge 40 plate 23 carries an inwardly projecting lug 30 having a slot 31. The lug 30 is adapted to enter a slot 32 in the window bar flange 13 and project thereto to the inside thereof.

The numeral 34 denotes a securing catch 45 mounted to slide on a screw 35. The edge 36 of the catch slides against the inside of the window bar flange 13. The latch has a bevelled nose 37 adapted to enter the slot 31 in the lug 30, and a finger piece 38. Normally 50 the latch engages the lug 30, the nose 37 passing through the slot 31 therein, and the window and movable hinge plate 23 are firmly se-

cured together. When it is desired to clean the window or for other reasons, the latch is pulled out of the lug 30 by tapping lightly on 55 the nose piece, and the window and hinge plate 23 being thus disconnected, the window may be swung on hinge 25 into the offset position shown in Figure 6.

At the bottom of the window, see Fig. 2, the 60 construction is the same as at the top but certain parts necessarily reversed.

From the foregoing it will be clear that this invention provides a casement window hinge which projects very little, and the windows may therefore be shipped without special provision to protect a projecting off-set hinge. 65

Again, means are provided for positively securing the window to the hinge, yet it may be quickly released and moved into off-set 70 position. It will also be observed that the securing or releasing of the window does not disturb the adjustment made with respect to tight fit. The construction also provides a hinge and window having all the advantages 75 of off-setting, yet when the window is operated normally and opened, there is only the usual small opening between the hinge edge 28 and the window frame, see Fig. 2. Whereas with off-set windows there is always a very 80 large opening at this point, permitting objectionable passage of wind and rain.

I claim:—

A hinge for metal casement windows comprising in combination a fixed hinge plate 85 adapted to be secured to a vertical portion of the window frame, said plate having an integral lateral extension plate adapted to be secured to a horizontal portion of the window frame, a hinge lug adapted to be secured to 90 the window, a movable hinge plate pivoted to and between said fixed hinge plate and lug, a slotted lug on the movable hinge plate adapted to enter through a slot in the window sash and project on the inside thereof, a slide 95 mounted on the sash and adapted to engage the slot in the movable hinge plate to secure the latter and the window together, and a screw in the window sash accessible from the inside when the window is opened for adjusting the sash relative to said movable hinge plate. 100

EDWIN J. SIBLEY.
